202,945

COMBINED LABEL PRINTER AND APPLICATOR

Heiko T. De Man, P.O. Box 304, Orinda, Calif.

Filed Nov. 9, 1964, Ser. No. 82,513

Term of patent 14 years

(Cl. D64—10)

FIG. 2 is a rear end elevational view thereof;

FIG. 3 is a front end elevational view thereof;

FIG. 4 is an elevational view of the side opposite to that of FIG. 1;

FIG. 5 is a top plan view; and

FIG. 6 is a bottom plan view thereof.

The broken line illustration of the tape is for illustrative purposes only.

The ornamental design for a combined label printer and applicator, substantially as shown and described.
